UNITED STATES PATENT OFFICE

FRIEDRICH SEUFERT, OF MUNICH, GERMANY, ASSIGNOR OF ONE-HALF TO HERMANN SEUFERT, OF BROOKLYN, NEW YORK

CINEMA OR ANALOGOUS PROJECTING APPARATUS

Application filed February 17, 1928, Serial No. 255,146, and in Germany October 22, 1927.

This invention relates to cinema or like projecting apparatus and particularly to the fire protective shutter of the gate.

One object of this invention is to provide hydraulic means insuring the prompt operation of the shutter.

Another object is to combine with said hydraulic means the pump for lubricating the different spindles of the apparatus.

10 With these and other objects in view my invention consists substantially in the novel construction, combination and arrangement of parts as will be hereinafter more fully described and defined in the appended claims.

15 In the accompanying drawing which constitutes part of this specification and in which similar reference characters denote corresponding parts, Fig. 1 is a diagrammatic vertical section of a part of the apparatus 20 showing the novel shutter operating means; Fig. 2 is a similar section at a right angle to that of Fig. 1 and Fig. 3 is a sectional top plan view thereof.

Referring to the drawings more in detail 25 10 denotes the frame and 11 the casing containing the gears for the operation of the sprocket drums 12 of which only one is shown in this drawing and over which the film is fed. 13 denotes the driving shaft which may 30 be driven from a motor (not shown) and which carries the fly wheel 14. This shaft 13 is formed with a worm 15 which meshes with a worm gear 16 fixed on the spindle 17 of the lower sprocket drum 12. 18 denotes 35 the conventional pump used for the distribution of a lubricant to the different operating spindles of the apparatus and which is operated from the spindle 17 in well known manner. 19 denotes a tube through which the 40 lubricant is passed from the pump 18 to branch tubes 20 leading to the different operating spindles of the apparatus and of which only one is shown in the drawings. Connected to the tube 19 is also a pressure cylinder 21 in which works a piston or plunger 22 which by a spring 23 acting thereon is normally held retracted and in its initial position tends to move the shutter 24 into closing position. To this end the shutter 24 is hinged 45 or pivoted at 24' to the frame 10 behind the

gate 25 and provided with a crank arm 26. The latter is connected by a link 27 to one arm of a bell crank lever 28 fulcrumed to the frame as at 28' and the other arm of which is connected by a link 29 to the piston rod 55 22'. The lubricant passing through tube 19 into the pressure chamber 21 is adapted to normally counteract the pressure of the spring 23 so as to move the piston forwardly and through the medium of the links 29, bell 60 crank 28 and link 27 swing the shutter 24 upwardly to open the gate 25. The pressure required to overcome the action of the spring 23 is controlled by means of a valve 30 provided between the pressure chamber 21 and the passage leading into the lubricating tubes 20. To this end the stem 31' of the valve body 31 projecting outwardly through the valve casing 31' carries at its threaded free end a nut 32 whereby the tension of the 70 spring 33 actuating said valve body 30 may be increased or decreased to permit the excess amount of oil or other lubricant entering the pressure chamber 21 to pass into the tubes 20.

It will be clear that if the pump 18 for 75 some reason fails to operate or its operation is interrupted the spring 23 moves the piston 22 into its initial position as a result of which the shutter 24 will close the gate 25.

It is understood that various changes may 80 be made in the construction of my apparatus without departing from the spirit of my invention. I, therefore, do not wish to restrict myself to the details shown and described.

What I claim is:

1. In a cinema or like projecting apparatus, the combination with the driving means and the shutter for the gate, of automatically controlled means for operating said shutter, said means including an element tending to close said shutter, a hydraulic pump operated from said driving means and adapted to normally counteract said element to hold said shutter open but on being interrupted in its operation, to release said element permitting it to effect the closure of said shutter, and pressure controlling means in said pump. 95

2. In a cinema or like projecting apparatus, the combination of the driving means, a lubricating pump driven from said means, a 100

fire protecting shutter for the gate, a pressure cylinder communicating with and adapted to receive the lubricant, a piston therein operatively connected to said shutter, a spring tending to retract said piston to close said shutter and adapted to be normally counteracted by the pressure of the lubricant pressing against said piston but on interruption of the operation of said pump to be released and permitted to effect the closure of said shutter and a controllable valve permitting the excess lubricant to pass from said cylinder to the parts to be lubricated.

3. In a cinema or the like projecting apparatus, the combination with driving means for said apparatus, of lubricating means driven by said first named means, a fire preventing shutter for the gate, means actuated by said lubricating means for opening said shutter when the former is being driven and automatic means for closing said shutter when said lubricating means is stopped.

In testimony whereof I affix my signature.
FRIEDRICH SEUFERT.
